UNITED STATES PATENT OFFICE.

MARTHA M. LIGHTFOOT, OF PLEASANT PLAINS, ILLINOIS.

DESIGN FOR A BODY MEMBER FOR CLOTHES-LINE PROPS.

SPECIFICATION forming part of Design No. 30,137, dated February 7, 1899.

Application filed February 26, 1898. Serial No. 671,860. Term of patent 7 years.

To all whom it may concern:

Be it known that I, MARTHA M. LIGHTFOOT, residing at Pleasant Plains, in the county of Sangamon and State of Illinois, have invented and produced a new and original Design for a Body Member for Clothes-Line Props, of which the following is a specification, reference being had to the accompanying drawing, forming part thereof.

10 My design relates to the main or body portion of a clothes-line prop, and is embodied in the unchangeable form or configuration of said body portion in its entirety as a definite article of manufacture.

15 The body portion of a clothes-line prop embodying my design is rectangular or box-shaped in form, its opposite sides being parallel for the greater part of their length. Two of the faces of the body member converge 20 near the upper extremity thereof, and their edges unite, as shown.

Surmounting the main portion of the body member is a member the upper part of which is in the form of a spiral and the lower part of which is in the form of a loop transverse 25 to the main part of the body member, as shown in the drawing.

That which I have invented and produced by my own industry, efforts, and expense, and that which I desire to secure by Letters Patent, is—

The design for a body member for clothes-line props as herein shown and described.

In witness whereof I have hereunto subscribed my name, at Pleasant Plains, Illinois, 35 this 23d day of February, A. D. 1898.

MARTHA M. LIGHTFOOT.
